UNITED STATES PATENT OFFICE

LOUIS H. MORIN, OF NEW YORK, N. Y., ASSIGNOR TO DOEHLER DIE-CASTING CO., A CORPORATION OF NEW YORK

ARMCHAIR

Application filed April 27, 1929. Serial No. 358,470.

The advantages of employing metal in the construction of articles of furniture are well recognized, but the development of metal furniture has been hampered by the high 5 cost of producing such articles as compared with like articles produced from wood, due, in a measure, to the necessarily intricate design of the parts in order to secure rigid joints between the members of the assembled 10 articles.

My invention relates especially to chairs constructed wholly of metal and one of the objects of the invention is to produce a chair of simple but pleasing design from a minimum 15 number of parts.

Another object is to produce rigid joints between the members of the chair.

A further object of my invention is to employ wherever possible sheet metal parts in 20 place of solid metal parts in order to decrease production costs.

Another important object is the provision 25 of a knock-down structure which may be readily assembled so that it may be shipped in knock-down form and the costs of shipment thereby minimized.

Other objects and advantages will be apparent from the following detailed description 30 of one embodiment of the invention.

In the drawings:

Fig. 1 is an elevation of the assembled chair having parts broken away to show some details of construction;

Fig. 2 is a section on line 2—2 of Fig. 1;

Fig. 3 is a section on the line 3—3 of Fig. 1;

Fig. 4 is a section on the line 4—4 of Fig. 1, with the seat member in section adjacent the seat frame and the right arm omitted;

Fig. 5 is an enlarged section on the line 40 5—5 of Fig. 4;

Fig. 6 is an enlarged fragmentary section on the line 6—6 of Fig. 1;

Fig. 7 is a section on the line 7—7 of Fig. 6;

Fig. 8 is a section on the line 8—8 of Fig. 6;

Fig. 9 is an enlarged section on the line 45 9—9 of Fig. 4;

Fig. 10 is an enlarged section on the line 10—10 of Fig. 4, and

Fig. 11 is an enlarged fragmentary section 50 on the line 11—11 of Fig. 4.

In the drawings, there is illustrated an armchair embodying my invention. The chair comprises, in general, a back member which constitutes the back and rear uprights, a back rest, a seat frame secured to the rear 55 uprights and having front leg members secured thereto, a seat member supported by said seat frame, and side arms secured to the rear uprights at one end and to the seat frame at the other end.

The back member 1 is preferably formed from steel tubing bent to the form shown which provides uprights connected by an arcuate upper cross member, the uprights extending down to form rear legs, as shown.

The back member so formed is bent outwardly appearing arcuate in profile and giving a graceful rearward tilt thereto which is conducive to the comfort of the occupant of the chair. The inner sides of the arcuate 60 cross member and the uprights are provided with openings to receive projections formed on the edges of a back rest 2.

The back rest may be, as desired, upholstered, caned, or as illustrated, of solid metal artistically 65 designed. Formed on the upper edge of the back rest 2, there are two vertical projections 3, and on each of the side edges there is a horizontal projection 4. The back rest

is assembled in the back by inserting the vertical projections 3 in the openings provided therefor in the cross member, forcing the uprights apart, bringing the horizontal projections 4 in alignment with the openings in 70 the uprights, and releasing the uprights which move inwardly, the projections entering the openings and the back rest being firmly secured in place by the resiliency of metal tubing from which the back is constructed.

At an appropriate point, somewhat below the horizontal center line of the back, a seat frame 5 is secured to the rear uprights by means of bolts 6. The seat frame 5 is desirably formed from solid metal being channel 75 shape in cross section as shown. Indentations are formed at the rear corners to receive the rear uprights and at this point the metal of the outer flange 7 is increased to strengthen the seat frame at the point of support. At

the forward corners, upwardly inclined extensions 8 support the lower ends of the arms. On the lower surface of the seat frame 5, at the forward corners, integral downward extensions provide conical downwardly flaring sockets 9 the upper ends of which form inner stop shoulders. These sockets are adapted to receive with a snug telescopic wedging fit the upwardly tapering conical upper end portions of tubular leg members 10, which are shown as gradually tapering downward from the sockets 9.

The leg members 10 are preferably formed from steel tubing which may be fluted if desired. At the lower end, the leg members 10 are provided with ornamental feet 11 which are formed from solid metal and are hollowed out at both ends leaving a solid central portion which is bored to receive a through bolt 12. The upper hollow portion of the foot member 11 provides an upwardly flaring socket which is adapted snugly telescopically to receive the lower end of the leg member 10, the bottom of this socket forming a stop shoulder against which the lower end of the leg abuts, and the lower hollow portion of the foot 11 being provided with a wooden plug 13 which rests on the floor. The foot 11 is placed over the lower end of the leg 10 and the through bolt 12 inserted in the bore in the solid central portion of the foot 11. The upper end of the leg is then inserted in the socket 9 in the seat frame and the bolt 12 entered in a theraded opening provided therefor. The bolt 12 is then screwed into the seat frame and tightly clamps the leg member between the foot 11 and the seat frame 5. The lower hollow portion of the foot is then closed by the wooden plug 13.

Arms, which are adapted to be secured to the back at one end to the overhanging portion 8 of the seat frame at the other end, are preferably formed from solid metal having solid ends 14 and 15, and an inverted channel shape portion 16 intermediate the solid ends. On the surface of that end 14, which is adapted to be connected to the rear upright, there is provided an overhanging tongue 17. The tongue comprises an upper rectangular portion substantially the width of the rear upright, the upper portion of which overhangs the upper edge of the arm, and a lower elongated rectangular portion adapted to be received in a slot provided therefor and resist lateral forces on the arms. Thus this tongue is of substantially the shape of the capital letter T. The rear upright is provided with an opening having the same general outline as the aforementioned tongue, being of slightly less length, so that, when the tongue is received within the opening, the overhanging portion engages the inner surface of the tubular upright above the opening therein. Also the lower narrower portion of this T-shaped tongue is at the same time snugly

received in the lower narrower portion of the T-shaped slot in the front wall of the tubular upright 1, with the adjacent end of the arm fitting closely against the front face of this upright (Figs. 6 and 7), so that thereby a firm and rigid connection is made between this upper rear end 14 of the arm and the tubular upright 1. Near the upper portion of the opening provided for the tongue the sides of the tubular upright are undercut substantially the thickness of the metal so that at the point where the surface of the arm and the surface of the upright meet they are coplanar and the curvature of the surface of the arm blends into the curvature of the surface of the upright. The lower end of the surface 14 is drilled and threaded to receive a special screw 18 by means of which it is held in contact with the surface of the upright. The rear surface of the upright is drilled to receive the elongated head of the screw 18 the end of which is flush with the surface of the upright in the assembled position. The lower end 15 of the arm is provided with a socket into which a projection 19 on the overhanging portion 8 of the seat frame 5 is received. The lug and socket are bored centrally to receive a bolt 20 which is threaded into the drilled opening in the arm and secures the end 15 to the seat frame. The lug 19 is adapted to relieve the bolt 20 of the shearing stresses which accompany lateral pressure on the arms.

A metal laced seat member 21 is bent at the edge thereof to form a flat depending and downwardly terminating flange 22 which is adapted to be secured between upflanged flat clamping strips 23 to the inner flat depending and downwardly terminating flange 24 of the channel-shaped seat frame 5. The seat clamps 23 are desirably formed from hot rolled round edge steel which is bent to the desired shape and dimensions. The flange 22 of the seat member is firmly clamped between these strips which are secured to the seat frame by bolts 25. The clamping strips 23 are continuous, as shown in Fig. 4. In effecting assembly, the inner strip 23 may be placed at the inner side of the seat flange 22, then the outer strip 23 may be pushed over the seat flange 22 from the side adjacent the seat member 21. Thereby there will be formed a unitary seat panel of which the clamping strips 23 will form the frame. A plurality of extensions 26, which are secured by means of tap bolts, as shown, to drilled and threaded lugs 27 formed on the lower surface of the seat frame 5 near the inner flange 24 thereof, extend inwardly at a right angle to the edge of the flange 24 and support the clamping strips together with the seat member.

The above described seat construction, as shown in the drawings, has a number of manufacturing and other advantages. Also the particular construction shown may be some-

what modified in some instances, where thought desirable for various reasons, while still retaining the major advantages. It has been found very convenient in manufacturing and assembling to make up as a separate and independent unit the panel comprising the metallic seat bottom 21 with its marginal flange 22 together with the inner and outer clamping strips 23 which form a panel frame therefor. The construction shown in the drawings provides for the assembly of this unitary seat panel with the seat frame 5 by carrying out either of two slightly different operations, according as may be found most convenient or desirable in any particular instance.

In one of these ways of effecting the complete assembly as shown in the drawings, the bolts 25 may be removed from or originally left out of the panel frame of the seat panel. Then, with the supporting lugs 26 projecting inwardly beyond the lower edge portion of the seat frame flange 24, as shown in the drawings, the seat panel unit may be pushed down from the upper side of the seat frame 5, with the outer seat panel frame strip 23 fitting snugly within the vertically flat surface of the inner seat frame flange 24, until the lower edges of the clamping strips 23 which form the seat panel frame abut against these projecting lugs 26. Then the bolts 25 may be inserted and their nuts tightened, as shown in the drawings, thereby not only preventing the possibility of accidental disassembly but also firmly and securely clamping together the inner clamping strip 23, the seat flange 22, the outer clamping strip 23 and the seat frame flange 24, thus providing in a convenient manner a strong and secure assembly of all of these parts.

In the particular illustrated construction and as shown in Fig. 4, it will be noted that a surrounding series of eighteen of the clamping and securing bolts 25 are provided and also that a similar series of thirteen of the supporting lugs 26 are provided in inter-spaced relation between the bolts 25. It may be further noted, as clearly indicated in Figs. 2 and 9 of the drawings, that these supporting lugs are notched upwardly into the lower edge of the seat frame flange 24, thereby preventing the possibility of these lugs becoming accidentally rotatively displaced on their securing bolts by which they are both displaceably and removably attached to the lugs 27, the lugs 26 being thus securely held in their projecting supporting position both before and after the assembly or installation of the seat panel in the seat frame 5.

In the construction shown in the drawings another way is provided by which the above noted assembly of the seat panel with the seat frame 5 may be effected, with the same final result. It will be noted, as shown in Figs. 2 and 9, that the openings in the seat frame

flange 24 for the bolts 25 are slotted downwardly through the lower edge of this flange 24. Therefore, in the course of manufacture, after the seat panel has been assembled with its clamping strips 23 in place, as hereinbefore described, the bolts 25 may be then placed in position on the seat panel frame, through the aligned apertures shown as provided in the seat flange 22 and clamping strips 23, with the nuts and lock-washers shown in the drawings in place upon these bolts, these nuts being either left loose upon the ends of the bolts or, if desired, for further security, they may be tightened down against the outer clamping strip 23 of the seat panel frame. Also the securing bolts for the supporting lugs 26 may be loosened or originally left loose, so that thereby these supporting lugs 26 may be turned on these bolts laterally aside and outwardly beyond the inner face of the seat frame flange 24.

Then in effecting assembly of the assembled seat panel, together with the bolts 25 carried thereby, with the seat frame 5, this seat frame may be placed conveniently in an inverted position and, with the nuts on the outer ends of the bolts 25, these bolts may freely pass into the slotted openings therefor in the seat frame flange 24, while the assembled seat panel frame is pushed into the seat frame 5 with the outer clamping strip 23 in snug engagement with the inner side of the seat frame flange 24. This outer clamping strip 23 thus enters the seat frame flange 24 from its free edge, which is the lower edge in the upright or normal position of the several parts shown in Figs. 2 and 9 of the drawings. Then the nuts on the combined clamping and securing bolts 25 are tightened, as before, after which, or before, it is immaterial, the supporting lugs 26 are moved to their inwardly projecting position shown in the drawings and their securing bolts are tightened, the assembly of the seat panel with the seat frame 5 then being complete.

It is obvious that if desired the slots shown in the lower edge portion of the seat frame flange 24 for the bolts 25 may be omitted and merely bolt apertures corresponding to the upper end portions of these slots then provided for these bolts. Also it should be obvious that, for the sake of further economy in manufacture, and if so desired in any particular instance, the outer clamping strip 23 might be omitted and the outer surface of the seat flange 22 then made to fit directly against the seat frame flange 24 and be clamped against it by the bolts 25. In such a more simplified construction the inner clamping strip 23 would by itself form a panel frame for the seat member 21 and the seat panel as a whole could thus be made up independently as a separate unit prior to its assembly with the seat frame 5. However, in such case, to assure this preliminary assembly

of the seat panel, the clamping bolts 25 should be placed in position on the seat panel with their nuts tightened down against the seat flange 22. Or instead, if desired, or in addition to the bolts 25, the flange 22 of the metal seat bottom 21 may be spot welded at intervals to the inner clamping strip 23, similar spot welding being commonly employed in the construction of various articles of metal furniture. However, the employment of the two clamping strips 23 as shown in the drawings provides a stronger and more secure preliminarily assembled seat panel, considered as a unit prior to its assembly with the seat frame 5.

The assembly of the armchair will be obvious from the above particular description.

It is obvious that various changes may be made in the construction illustrated in the drawings and above particularly described, within the principle and scope of my invention as expressed in the appended claims.

I claim:

1. In a chair or the like, the combination of a tubular rear upright, a seat frame secured to the said upright, an arm having its rear upper end shaped to fit against the front face of the said upright, a T-shaped locking tongue projecting inwardly and upwardly from such end of the arm and provided at its upper end with an upwardly projecting overhanging portion, the front wall of the said tubular upright being provided with a T-shaped slot with the upper end of this slot terminating below the upper end of the said T-shaped tongue so that thereby the upwardly projecting overhanging end portion of the tongue will have an interlocking engagement with the inner side of the front wall of the tubular upright above the said slot therein with the said T-shaped tongue as a whole projecting to the inside of the tubular upright through such T-shaped slot and with the adjacent end face of the arm abutting against the front face of the upright, and means for securing the lower front end of the said arm to the said seat frame.

2. In a chair or the like, the combination of a seat member having a flat surrounding depending downwardly terminating flange, and separate inner and outer clamping strips having opposed flat surfaces between which the seat flange is received and clamped with the lower edges of the said strips substantially coterminous with the lower edge of the seat flange thereby to form a unitary seat panel of which the said clamping strips form a panel frame.

3. In a chair or the like, the combination of a seat member having a flat surrounding depending downwardly terminating flange, separate inner and outer flat clamping strips between which the seat flange is received and clamped with the lower edges of the said

strips substantially coterminous with the lower edge of the seat flange thereby to form a unitary seat panel of which the said clamping strips form a panel frame, a seat frame having an inwardly flat depending downwardly terminating flange on the inner edge thereof and within which the said seat panel removably fits with the outer clamping strip in engagement with the inner side of the said seat frame flange, and a surrounding series of securing and clamping bolts passing through all of the said flanges and strips. 70 75

4. In a chair or the like, the combination of a seat member having a flat surrounding depending downwardly terminating flange, separate radially inner and outer unflanged flat clamping strips between which the seat flange is received and radially clamped thereby to form a unitary seat panel of which the said clamping strips form a panel frame, a seat frame having a flat depending downwardly terminating flange on the inner edge thereof and within which the said seat panel removably fits with the outer clamping strip in engagement with the inner side of the said seat frame flange, a surrounding series of securing and clamping bolts passing through all of the said flanges and strips, and a surrounding series of supporting lugs for the seat panel displaceably secured to the lower side of the seat frame to project inwardly beyond the lower edge portion of its said flange. 80 85 90 95

5. In a chair or the like, the combination of a seat member having a flat surrounding depending downwardly terminating flange, separate radially inner and outer unflanged flat clamping strips between which the seat flange is received and radially clamped thereby to form a unitary seat panel of which the said clamping strips form a panel frame, a seat frame having a flat depending downwardly terminating flange on the inner edge thereof and within which the said seat panel removably fits with the outer clamping strip 100 105 110 115 120 125 in engagement with the inner side of the said seat frame flange, a surrounding series of securing and clamping bolts passing through all of the said flanges and strips, and a surrounding series of supporting lugs for the seat panel displaceably secured to the lower side of the seat frame to project inwardly beyond the lower edge portion of its said flange, the said flange of the seat frame being provided with downwardly opening slots below and extending up to the said bolts for the entrance and removal of these bolts through such slots in the displaced condition of the said supporting lugs.

In witness whereof, I hereunto subscribe my signature.

LOUIS H. MORIN.
